UNITED STATES PATENT OFFICE.

ALFRED SEALE HASLAM, OF DERBY, ENGLAND.

FLUID COMPRESSOR.

1,408,593.

Specification of Letters Patent. Patented Mar. 7, 1922.

Application filed February 15, 1921. Serial No. 445,181.

To all whom it may concern:

Be it known that I, ALFRED SEALE HASLAM, a subject of the King of Great Britain, residing at Breadsall Priory, Derby, England, have invented new and useful Improvements in Fluid Compressors, of which the following is a specification.

This invention relates to apparatus for compressing gases where more than two pressures are employed, and more particularly to refrigerating apparatus using as a refrigerating agent carbon dioxide, ammonia or other fluid and working on what is known as the "multiple effect" system where the compressor cylinder is supplied with gas from two or more sources at different pressures, the gas at the higher pressure being admitted into the cylinder so as to bring the pressure up to the highest value before the compression stroke.

In such apparatus, fluid passes from a condenser through an expansion valve or cock into a receiver which is used to separate the liquid from the gas which is formed at the expansion valve above mentioned. The gas so formed passes away from the top of the receiver to the compressor and the liquid falls to the bottom and passes a second expansion valve or cock to the evaporator.

According to this invention the two expansion valves or cocks are so arranged that they may be simultaneously adjusted at one operation.

In one method of carrying out the invention, two parallel valves are connected either directly or through levers to a single regulating screw. The pivot of one of the levers may be adjustable so that the ratio of the opening of the two valves may be varied.

The valve seats may also be made adjustable so that the valve openings can be altered independently of the regulating screw.

In another method the two valves are formed on one spindle capable of endways adjustment either by a screw thread on the spindle or preferably by means of a differential thread which gives a more sensitive adjustment.

The valve spindle and the seats are preferably made of a self hardening steel so as to resist the wear due to the high speed of the gases passing through.

A suitable division plate is preferably provided between the valve seats in order to direct the gas given off at the first valve

towards the top of the receiver, and to ensure a supply of liquid to the outlet valve.

The annexed drawings illustrate two methods of carrying out the invention.

Figure 1 is a diagrammatic view of a multiple effect apparatus.

Figure 2 is a section of an apparatus in which two parallel valves are employed and Figure 3 is a section in which two valves are mounted on one spindle.

In Figure 1, A is a compressor connected to a condenser C and R is a multiple effect receiver connected to the condenser C and to an evaporator E, the flow being regulated by two simultaneously adjusted expansion valves V. The receiver R and evaporator E are also connected to the compressor A as shown.

The present invention relates to the construction of the valves V examples of which are shown in Figures 2 and 3.

In Figure 2 a valve a is held on its seat b by a lever c pivoted at d and another valve e parallel to the valve a is held on its seat f by a lever g pivoted at h and to which the valve e is connected by a pivot j. The movement of the valves a and e is adjusted by a regulating screw k which engages with the lever g whereby both valves can be adjusted at one operation. The pivot d of the lever c is carried by a screw rod l by which the pivot d can be moved so that the ratio of the opening of the two valves a and e may be varied. Fluid from the condenser C enters through a passage m through the valve a to the receiver R and the gas formed passes away through an outlet o to the compressor A and the liquid passes the valve e to the outlet p leading to the evaporator E. The valve seats b and f are carried by screw rods q and r respectively so that the valve openings can be altered independently.

Referring to Figure 3 the valves a and b having seats c and d respectively are formed on a spindle e capable of endways adjustment by means of a screw thread f on the spindle e engaging with a screw thread g on the rod h having another screw thread j engaging with a screw thread k on its socket, the threads f and g being of less pitch than the threads j and k. The spindle e is prevented from turning by the pin l. Liquid from the condenser C enters an inlet m, flows past the valve a into the receiver R and the gas formed passes out through an

outlet *n* to the compressor A whilst the liquid passes the valve *b* to an outlet *o* leading to the evaporator E. A division plate *p* is provided between the seats *c* and *d* of the valves in order to direct the gas given off at the valve *a* towards the top of the receiver R and to ensure a supply of liquid to the valve *b*.

What I claim is:—

- 10 1. In apparatus for compressing gases of the type specified, a condenser, a multiple effect receiver, a valve controlled connection between the condenser and receiver, an evaporator, a valve controlled connection between the receiver and the evaporator and means for simultaneously adjusting the valves.
- 15 2. In apparatus for compressing gases of the type specified, a condenser, a multiple effect receiver, a valve controlled connection between the condenser and receiver, an evaporator, a valve controlled connection between the receiver and the evaporator, a spindle carrying both valves, and means for
- 20 25 moving the spindle endwise.

3. In apparatus for compressing gases of the type specified, a condenser, a multiple effect receiver, a valve controlled connection between the condenser and receiver, an evaporator, a valve controlled connection 30 between the receiver and the evaporator, a spindle carrying both valves, means for moving the spindle endwise and a division plate in the receiver between the valves.

4. In apparatus for compressing gases of 35 the type specified, a condenser, a multiple effect receiver, a valve controlled connection between the condenser and receiver, an evaporator, a valve controlled connection between the receiver and the evaporator, a 40 spindle carrying both valves, a screw thread on the spindle engaging with a screw thread on a rod, and another screw thread on the rod engaging with a screw thread on its socket.

In testimony that I claim the foregoing as my invention, I sign my name this fifteenth day of December, 1920.

45 ALFRED SEALE HASLAM.
